(57) **CLAIM**

The ornamental design for a flow cell carrier, as shown and described.

DESCRIPTION

FIG. 1 is a top perspective view of a flow cell carrier, showing the new design;

FIG. 2 is a bottom perspective view of the flow cell carrier shown in FIG. 1;

FIG. 3 is a top plan view of the flow cell carrier shown in FIG. 1;

FIG. 4 is a bottom plan view of the flow cell carrier shown in FIG. 1;

FIG. 5 is a right side elevation view of the flow cell carrier shown in FIG. 1;

FIG. 6 is a left side elevation view of the flow cell carrier shown in FIG. 1;

FIG. 7 is a rear elevation view of the flow cell carrier shown in FIG. 1;

FIG. 8 is a front elevation view of the flow cell carrier shown in FIG. 1; and,

FIG. 9 is a top perspective view of the flow cell carrier shown in FIG. 1 having no flow cell carried therein.
